By G. A. Gray Atty

UNITED STATES PATENT OFFICE.

WALLACE S. WARNOCK, OF CHICAGO, ILLINOIS.

PRINTING-ELEMENT HOLDER.

1,406,787.

Specification of Letters Patent. Patented Feb. 14, 1922.

Application filed November 5, 1921. Serial No. 512,963.

To all whom it may concern:

Be it known that I, WALLACE S. WARNOCK, citizen of the United States, residing at Chicago, in the county of Cook and State 5 of Illinois, have invented a certain new and useful Improvement in Printing-Element Holders, of which the following is a full, clear, concise, and exact description.

My invention relates to printing element 10 holders, commonly termed printing plate holders, and has for its general object the provision of simplified mechanism entering into the construction of the holder so that the holding jaw thereof may readily be applied 15 to a plate or other printing element to be clamped thereby.

In practicing my invention I employ a hollow carrier, a clamping jaw upon the carrier and having a stem within and in 20 pivotal connection with the carrier, an arcuate rack within the carrier and substantially co-axial with the jaw stem, and operating gearing upon and travelling with the clamping jaw and co-acting with said 25 rack to effect travel of the jaw.

In the preferred embodiment of the invention the stem of the jaw is bifurcated and there are two arcuate racks between which the jaw stem is mounted to move. The 30 gearing that travels with the jaw and co-operates with the rack to effect movement of the jaw is preferably inclusive of two co-axial pinions in mesh with the racks, a gear between and mechanically connecting the 35 pinions and co-axial therewith and a worm screw in mesh with the gear and accessible for operation through the jaw.

I will explain my invention more fully by reference to the accompanying drawing 40 showing the preferred embodiment thereof and in which Fig. 1 is a vertical sectional view, on a large scale, of a printing plate holder constructed in accordance with the invention and a portion of a printing plate 45 foundation that receives the holder; Fig. 2 is a sectional view on line 2-2 of Fig. 1 minus the printing plate foundation; Fig. 3 is a sectional view on line 3-3 of Fig. 1 also minus the printing plate foundation; 50 and Fig. 4 is a plan view showing a portion of a section of a printing plate foundation with a printing plate holder of my invention assembled therewith.

Like parts are indicated by similar characters of reference throughout the different 55 figures.

The printing bed or foundation may be of any suitable shape, the drawing showing a section 1 of a flat bed, a number of sections suitably assembled forming the bed. 60 Each of these sections or blocks is formed with a plurality of cylindrical holes 2, in the construction of the bed section illustrated, although it is to be understood that the invention is not to be limited to any 65 particular form of bed nor to the shape of the holes 2 therein. As illustrated, each hole is provided with an annular enlargement 3 below the work supporting face of the bed whereby there is provided in each 70 hole an annular retaining shoulder 4. Carriers 5 are used in sufficient number to hold the printing plate upon the bed, these carriers supporting the work engaging mechanism that is to be described. The carriers 75 are preferably cylindrical in order that they may be snugly received within the holes within which they are rotatable in order that the work engaging mechanism may be positioned to suit the location of the work 80 that is to be held upon the foundation.

The mechanism is inclusive of an actuating element 6 within the carrier and slideable along the same, this actuating element having two ears 7 each formed with an inclined 85 slot 8, the slots being in the same inclined plane and receiving a pin 9 that is carried by the upright wings 10 of a retaining member 11. Said wings are formed with horizontal elongated slots or openings 12 through 90 which the rod 13, that is within and anchored to the shell, is passed. The actuating element 6 is formed with an opening 14 for the reception of a projection upon a suitable actuating tool whereby movement 95 of the actuating element may be forced. When the actuating element is drawn to its outermost position the lower portions of the slots 8 are positioned to receive the pin 9. Said pin, being fixed upon the wings 100 10, will then force the inward movement of these wings as the pin is brought to the lower ends of the slots 8 whereby the retaining member is withdrawn sufficiently 105 into the carrier 5 to permit of the insertion 110 and removal of the same. When the carrier is to be assembled with the printing plate foundation it is lowered to a position in which the plane of the retaining member 11 is below the shoulder 4, the actuating element 6 being then withdrawn to its uppermost position to withdraw the retaining

member sufficiently into the shell to permit it to clear the bed. When the retainer is thus positioned the actuating element is depressed to cause the upper ends of the slots

5 8 to receive the pin 9 in which operation the wings 10 are moved outwardly to thrust the retaining member 11 beneath the retaining shoulder 4 upon the bed. When the parts are thus assembled the plate holding mechanism, now to be described, may be suitably adjusted.

This plate holding mechanism is inclusive of a clamping jaw 15 upon the carrier 5 and having a bifurcated stem 16 within and

15 in pivotal connection with the carrier, the stem desirably being in pivotal or rotative connection with the rod 13 that is surrounded by the lower end of the stem. Two arcuate racks 17 are within the carrier with

20 which they are assembled by means of the rivets 18, the distance preserving sleeves 19 that surround the rivets defining the spaces that intervene between the racks and the carrier. These racks are co-axial with the

25 jaw stem 16 and the pivot rod 13 of said jaw stem. I provide operating gearing upon and traveling with the clamping jaw 15 and co-acting with the racks 17 to effect the travel of the jaw. Said gearing includes

30 two co-axial pinions 20 in mesh with the racks 17, a gear 21 between and mechanically connecting the pinions and co-axial therewith, and a worm screw 22 in mesh with the gear 21 and accessible for operation through the jaw, the common axis of

35 the gear elements 20 and 21 being horizontal and the axis of the worm screw 22 being vertical or transverse to the direction of travel of the jaw. The upper end of the

40 screw 22 is formed with a continuation 23 that is polygonal in contour, the jaw having an upright passage therethrough that receives not only the screw 22 but also its continuation 23 that is made accessible for engagement therewith by a jaw adjusting tool.

45 The lower end 24 of the screw 22 is journaled in the base of the hook 25, the screw end 24 being of lesser diameter than the screw so that the screw is prevented 50 from dropping and having a head 26 at its lower end to prevent the screw from rising.

While I have herein shown and particularly described the preferred embodiment of my invention I do not wish to be limited to 55 the precise details of construction shown as changes may readily be made without de-

parting from the spirit of my invention, but having thus described my invention I claim as new and desire to secure by Letters Patent the following:—

60

1. A printing element holder including a hollow carrier; a clamping jaw upon the carrier and having a stem within and in pivotal connection with the carrier; an arcuate rack within the carrier and substantially co-axial with the jaw stem; and operating gearing upon and travelling with the clamping jaw and co-acting with said rack to effect travel of the jaw.

65

2. A printing element holder including a hollow carrier; a clamping jaw upon the carrier and having a stem within and in pivotal connection with the carrier; an arcuate rack within the carrier and substantially co-axial with the jaw stem; and operating gearing upon and travelling with the clamping jaw and co-acting with said rack to effect travel of the jaw, said gearing including a pinion in mesh with the rack, a gear coupled with the pinion and a worm screw in mesh with the gear and accessible for operation through the jaw.

70

3. A printing element holder including a hollow carrier; a clamping jaw upon the carrier and having a bifurcated stem within and in pivotal connection with the carrier; two arcuate racks within the carrier and substantially co-axial with the bifurcated jaw stem that is disposed between the racks; and operating gearing upon and traveling with the clamping jaw and co-acting with said racks to effect travel of the jaw.

75

4. A printing element holder including a hollow carrier; a clamping jaw upon the carrier and having a bifurcated stem within and in pivotal connection with the carrier; two arcuate racks within the carrier and substantially co-axial with the bifurcated jaw stem that is disposed between the racks; and operating gearing upon and traveling with the clamping jaw and co-acting with said racks to effect travel of the jaw, said gearing including two co-axial pinions in mesh with the racks, a gear between and mechanically connecting the pinions and co-axial therewith and a worm screw in mesh with the gear and accessible for operation through the jaw.

80

5. In witness whereof, I hereunto subscribe my name this 2nd day of November, A. D. 110 1921.

WALLACE S. WARNOCK.
